Primary Examiner — Dana K Weiland*Assistant Examiner* — Emily Anna Saunders(74) *Attorney, Agent, or Firm* — Belles Katz LLC(57) **CLAIM**

The ornamental design for a bubble machine, as shown and described.

DESCRIPTION

FIG. 1 is a front perspective view of a bubble machine according to my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dashed lines illustrate portions of the bubble machine that form no part of the claimed design. The dot-dash broken lines define the bounds of the claimed design and form no part thereof.
